P. A. SCHWAB.
AUTOMOBILE BODY CONSTRUCTION.
APPLICATION FILED JULY 14, 1917.

1,323,790.

Patented Dec. 2, 1919.

UNITED STATES PATENT OFFICE.

PETER A. SCHWAB, OF NEW YORK, N. Y., ASSIGNOR TO ADAMS-WILLIAMS MANUFACTURING CORPORATION, OF NEW YORK, N. Y., A CORPORATION OF NEW YORK.

AUTOMOBILE-BODY CONSTRUCTION.

1,323,790.

Specification of Letters Patent.

Patented Dec. 2, 1919.

Application filed July 14, 1917. Serial No. 180,489.

To all whom it may concern:

Be it known that I, PETER A. SCHWAB, a citizen of the United States, and resident of New York city, in the county of New York and State of New York, have invented certain new and useful Improvements in Automobile-Body Constructions, of which the following is a specification.

This invention is an improvement in automobile body construction and relates to the means for detachably securing in place the transparent panels used in converting the body into either an open touring car or a closed limousine. The invention is particularly adapted to that type shown in the Williams Patents Nos. 1,151,314 and 1,151,315 of August 24th, 1915, in which the panels have rigid frames with depending lugs for insertion in sockets in the upper edges of the hinged or stationary wall sections of the body.

By means of my invention, I provide a rigid construction, inexpensive to manufacture, attractive in appearance and easy to apply to the various types of open touring cars during manufacture or after being completed and in use and constituting a practical method of holding the frames without the use of special sills and with clamping members entirely concealed. The details of merely one embodiment of my invention will be explained in connection with the accompanying drawings in which—

Figure 1 is a side elevation of a body construction in connection with which my improved construction might be employed;

Fig. 2 is a perspective view of a portion of the wall section, the molding strip being longitudinally displaced;

Figs. 3 and 4 are transverse sections in parallel planes indicated by the lines 3—3 and 4—4 respectively of Fig. 5;

Fig. 5 is a horizontal section on the line 5—5 of Fig. 4 showing the end portions of the molding strip, the center portion being broken away; and Fig. 6 is a side elevation of the upper edge of the wall and the lower edge of the panel in spaced relationship.

In Fig. 1, I have shown a portion of an automobile having the usual body including stationary wall sections 10 and 11, and intermediate hinged wall sections or doors 12 and 13. The body at its rear supports the frame work of a type of top commonly known as a "one-man" top 14 and which has

a horizontal bow extending substantially parallel to the upper edge of the body proper and secured to the upper edge of the wind shield stanchions 15. Intermediate these stanchions and an upwardly extending bow 16 of the top, there are provided four panels 17, 18, 19 and 20, corresponding to the four body sections 10, 11, 12 and 13 and each rigidly secured to its corresponding wall section.

These panels include rigid frames carrying transparent plates of glass, celluloid or other substance suitable for the purpose. The upper edges of the panels 17 and 18 which are carried by the stationary parts of the body may be secured to the horizontal bow of the top in any suitable manner if desired, while the panels 19 and 20 being carried by the hinged wall sections or doors 12 and 13 are preferably not secured to the top but may resiliently press against it as the doors are closed.

The wall sections 10, 11, 12 and 13, may vary in number and width, depending upon the type of car. In bodies with only a single door, there may be three panels, one carried by the door and one carried by the stationary wall section in advance of and one in the rear of said door. In other body constructions, no panel in front of the door need be employed and thus there would be only two panels on each side, one carried by the door and the other carried by the stationary wall in the rear of the door.

The features of construction so far referred to in detail form no portion of my invention and are illustrated and described merely to facilitate a clear understanding of a preferred use of my invention.

The wall sections, whether stationary or hinged are ordinarily formed of a wooden frame 21 with an outer sheet metal covering 22 which is ordinarily folded or rounded over the frame at the upper edge of the latter to give the wall section a smooth and attractive finished appearance and to conceal and protect the frame. My invention relates particularly to a form of molding strip which may be embodied in the car at the time the body is built or may be substituted for such finishing strip as may be embodied in the car or may be directly attached to the finished upper edge of the wall section. In the specific form illustrated, my improved construction includes a block 23, 110

preferably of cast metal and of a width substantially equal to the desired width of the molding. Preferably, the opposite side edges are rounded or curved to avoid the presentation of sharp angles. The block may be of any desired length, although preferably it is merely of sufficient length to give the desired rigidity and strength. It has a vertical slot 24 adjacent to the outer side 5 and a recess 25 in the opposite or inner vertical edge. Extending from the recess 25 to the vertical slot 24 is a substantially horizontally disposed threaded passage 26. At suitable points in the block are vertically 10 disposed apertures through which screws 27 or other fastening means may be inserted down into the wood or other material forming a rigid part of the wall section. The block preferably extends only a small proportion 15 of the distance between the ends of the wall section and preferably two blocks are employed for each wall section, one being disposed closely adjacent to and preferably flush with the corresponding vertical edge of the wall section. The opposite ends 20 of each block may be cut at such angles that the blocks are interchangeable whereby either block may be secured adjacent to either edge of the wall section.

25 In connection with the plurality of blocks on each wall section, I provide a sheet metal molding strip of a length substantially equal to the wall section and of a cross sectional form adapting it to slide endwise over the blocks and be held in place thereof. As shown, this strip 28 has curved side 30 walls with inturned flanges 29 adapted to slide within undercut grooves 30 in the lower surface of the block whereby the strip may be removed only by a longitudinal or sliding movement. The strip has a 35 pair of slots 31 corresponding to the two slots 24 of the two blocks and may and preferably does have a longitudinally extending bead 32 serving as a weather strip as will be more particularly pointed out hereinafter.

40 Each panel has a rigid frame 33 presenting depending lugs 34 rigid with the frame and corresponding in number and size to the slots 24 in the blocks 23. The lugs are preferably of a height slightly less than the depth of the slots 24 and of such cross-sectional area that they may be readily inserted in or withdrawn from the slots.

45 For rigidly holding them in place within said slots, each block has a clamping screw 35 extending through the threaded aperture 26. Upon tightening this screw, the end 50 engages with the side of the lug 34 and firmly binds the latter against the far side of the slot and holds the panel against removal or lateral movement. The screw 35 may be of such length as to project beyond 55 the side of the block 23 and may have its

outer end so designed as to be readily grasped in the hand to loosen or tighten the same. Preferably the screw has a head portion 36 non-circular in cross section and disposed within the recess 25. The molding 60 strip 28 has an aperture 37 in alignment with the screw and somewhat larger than the latter so that a key may be inserted through the aperture 37 into the recess 25 and engage with the screw to loosen or 65 tighten the latter. When loosened the panel has sufficient free play to permit the lateral movement of the upper edge of the panel in case it is desired to swing the latter outwardly from beneath the top 14 before lifting the lugs 34 out of the slots 24. With the panel in place, it rests directly upon the molding strip and the lugs of the panel are concealed within the slots. The bead 32 prevents rain-water from beating in under the edge of the panel as will be apparent from Fig. 3 and the recess 25 serves to conceal the end of the clamping screw so that there are no projecting parts upon 70 which one may catch his clothing in getting 75 in or out of the car. The heavy screws or other fastening means which retain the blocks 23 in position are entirely concealed by the molding strip 28. The entire strain 80 of clamping and supporting the panels is 85 borne by the heavy blocks rather than by the light sheet metal molding. The molding may be held in position and against longitudinal sliding movement in a suitable manner, as for instance, by means of a small 90 single retaining screw 39 as shown in Figs. 4 and 5.

95 It will be apparent that the cross-sectional form of the blocks and molding strip is of no particular importance so far as my invention is concerned, as such cross-sectional form may be varied in accordance with the character of the car to which the invention is applied. Preferably, the molding strip does entirely cover the blocks except for the 100 ends of the latter and so engages with the blocks as to prevent removal except by sliding endwise.

105 Having thus described my invention, what I claim as new and desire to secure by 110 Letters Patent, is:

115 1. A convertible automobile body including a wall section, a removable panel having a plurality of depending lugs, a plurality of separate members rigidly secured to the 120 upper edge of said wall section and each having a lug receiving socket therein, separate means for clamping each lug within its corresponding socket and a molding strip longitudinally slidable over said members to 125 cover the same and having lug receiving apertures registering with said sockets.

130 2. In combination, a wall section, a removable panel having a pair of depending lugs, a pair of blocks secured to the upper

edge of said wall section at spaced points and each having a lug receiving socket, a molding strip slidable endwise over said blocks to inclose the latter and having apertures registering with the sockets of said blocks, and separate means for clamping each lug within its socket.

3. In combination, a wall section, a removable panel having a pair of depending lugs, a pair of blocks secured to the upper edge of said wall section at spaced points and each having a lug receiving socket, a molding strip slidable endwise over said blocks to inclose the latter and having apertures registering with the sockets of said blocks, and separate means for clamping each lug within its socket, said means being carried by said blocks and inclosed within said molding strip.

20 4. In combination, a block adapted to be secured to the upper edge of a wall section, and having a lug receiving socket therein and a clamping member extending into said socket for clamping engagement with the lug in the latter, and a molding strip slidable endwise over said block and having an aperture registering with said socket and an aperture registering with said clamping member.

30 5. In combination, a block having a lug receiving socket extending substantially vertically, a recess in one side edge thereof, and a threaded passage extending from said recess to said socket, a clamping member extending through said aperture and having one end terminating in said socket and having a head disposed within said recess and a molding strip covering said block and having an aperture registering with said socket and a second aperture registering with said recess.

45 6. In combination, a block having a vertically disposed socket in the upper surface thereof and a threaded aperture extending substantially horizontally to said socket, a

threaded clamping member within said aperture having one end terminating in said socket and a molding strip having depending side walls terminating in inwardly turned edges slidable beneath the side edges 50 of said block.

7. In combination, a vehicle body wall, a block secured to the upper edge thereof, and having a lug receiving socket extending substantially vertically, a recess in one side edge 55 thereof, and a threaded passage smaller than said recess and extending therefrom to said socket, and a clamping member extending through said aperture and having one end terminating in said socket and having a head disposed within said recess.

8. A convertible automobile body including a wall section, a removable panel having a pair of spaced depending lugs, a pair of spaced members separately secured to the upper edge of said wall section and each having a socket therein, clamping members adapted to engage with said lugs when the latter are within said sockets, and a removable strip extending along the upper edge of 75 said wall section and covering said members and having apertures registering with said sockets.

9. A convertible automobile body including a wall section, a removable panel having 75 a pair of depending lugs, a pair of members, means for securing them to the upper edge of said wall section at spaced points, each of said members having a lug receiving 80 socket and a threaded aperture intersecting the same, a sheet metal strip covering said first mentioned members and said securing means and having apertures registering with said sockets and said passages, and clamping members within said threaded 85 passages.

Signed at New York city, in the county of New York, and State of New York, this 9th day of July, A. D. 1917.

PETER A. SCHWAB.
